UNITED STATES PATENT OFFICE.

JACK J. BRAZ, OF BROOKLYN, NEW YORK, ASSIGNOR TO AMERICAN METAL PRODUCTS CO., OF NEW YORK, N. Y., A PARTNERSHIP COMPOSED OF JACK J. BRAZ AND NATHAN A. LEVITAN.

SMOKER'S STAND.

Application filed February 13, 1928. Serial No. 253,841.

This invention relates to a smoker's stand. I am aware that heretofore stands for the use of smokers have been constructed in various manners to include a rest or support for a 5 cigar, cigarette, or a pipe, and also a match box rack or support and an ash tray. In some instances the ash tray includes a receptacle or a dish made of glass or other similar material but the receptacle is fixed to the other portions 10 of the stand and consequently is not separably removable therefrom for the purpose of emptying the ashes and otherwise cleaning the tray. Obviously in such structures in cleaning the ash tray receptacle it is necessary to 15 handle the entire stand and this often times is cumbersome, making the task more or less difficult. The object of my present invention is to provide a stand for smokers and to construct the same in such a manner that the 20 parts are readily assembled for use and the ash tray or trays separable removable for the purpose of facilitating the cleaning thereof, as will be hereinafter more particularly described.

25 In the drawing Figure 1 is a sectional elevation illustrating a smoker's stand made in accordance with my invention,

Figure 2 is a plan of the same,

Figure 3 is a section on line 3—3, Figure 1, 30 and

Figure 4 is a perspective view showing the upper parts of the stand when disconnected.

By reference to the drawing it will be seen that in carrying out the invention the smoker's stand made in accordance therewith includes a base 10 which in suitably spaced positions may be provided with feet 11. The stand also includes an upright or shank member 12 having at its lower end a reduced portion 13 adapted to pass through an opening provided therefor in the boss 14 at the underside of the base so that the upright or shank may be secured to the base by means of a nut 15 or otherwise.

45 The upper end of the shank 12 is also provided with a stem of reduced cross-section, as indicated at 16, and which is provided with a screw thread. Fitted to the upper end of the shank there is a head 17. In the head 17 there is a hole or opening 18 through which the reduced screw threaded stem 16 is adapted to pass in order that the head may rest upon the shoulder at the upper end of the shank.

50 The head is secured in position on the shank 55 by a cap 19 provided with a tapped socket to

be turned down on the screw threaded end 16 to secure the parts together. As illustrated, the cap 19 may include a ring 20 that may be utilized as a handle.

The head 17 is made to include an extension 60 21 provided with a match box holder 22. In a position oppositely disposed to the extension 21 the head 17 is formed to include a pipe or cigar holder, as indicated at 23. Associated with the head 17 I also employ ash trays 24 65 and 25 each of which, as illustrated, may be formed to include a cigar or cigarette rest 26 and 27.

The ash trays 24 and 25 are detachably and interchangeably connected to the head 17, and 70 as the construction of both is similar it will be described merely in connection with the ash tray 25. To this end the head 17 is provided with a recess 28 and spaced supports 29 and 30, which are adjacent the outer portion of 75 the head in which the recess is placed, the upper face of these supports being appreciably below the top surface of the head. In a suitable position the tray 25 is provided with an angular lug 31. Beneath this lug 31 there 80 is a rib 32. The lug 31 is so constructed that distant from its outer face there are shoulders 33 and 34 while the rib 32 extends beyond the outer face of the lug 31 to provide a lip 35. These parts are so constructed that the width 85

of the lug 31 is substantially the same as the width of the recess 28, while the depth of the recess is substantially equal to the distance between the outer face of the lug 31 and the shoulders 33 and 34. In placing the tray in 90 position, therefore, the lug 31 is set in the recess 28 so that the rib depending from the angular lug lies between the supports 29 and 30 and the upper faces of these supports contact with the inner surface of the lug, while 95 the shoulders 33 and 34 abut against the outer edge of the head 17, and the lip 35 projects beneath the adjacent portion of the head 17 which, if necessary, may be cut away to receive the same. It will now be understood 100

that the tray 25 may be readily connected and disconnected to and from the head 17 and is normally supported in position by the parts hereinbefore described. In removing the tray or in placing the same in position it is 105 necessary to only tilt the same slightly relatively to the head whereby it may be put in place and as easily removed from the head for the purposes of cleaning it independently of the other parts of the stand or otherwise. It 110

will also be understood that the parts of the stand may be readily disconnected for the purposes of packing and shipping or otherwise and that they may be as readily assembled to their positions for use.

I claim as my invention:

1. In combination with a support member having a recess in the side thereof with spaced supporting lugs in the recess, of a tray having a lug and a depending rib extending beyond the lug to form a lip, the said lug on the tray being adapted to fit within the recess of the support member and to rest upon the supporting lugs therein with the lip extending beyond the lug of the tray engaging the inner surface of the support member whereby the tray is adapted to be detachably maintained in position relatively to and by the support member.
2. In combination with a support member

having a recess in the side thereof and spaced supporting lugs lying within the recess with portions thereof appreciably below the outer surface of the said support member, of a tray having a lug with an underlying rib which extends beyond the face of the lug to form a lip, the lug of the tray being adapted to fit within the recess in the support member and to bear against the outer ends of the said supporting lugs thereof, and the underlying rib on the lug of the tray fitting between the supporting lugs of the support member and the said lip engaging the inner surface of the said support member whereby the tray is detachably maintained in position relatively to and by the said support member.

Signed by me this 19th day of January, 1928.

JACK J. BRAZ.
